(57) **CLAIM**

The ornamental design for a toilet paper holding device, as shown and described.

DESCRIPTION

FIG. 1 is a right front perspective view of the design for a toilet paper holding device, showing my new design.

FIG. 2 is a right side elevational view thereof.

FIG. 3 is an exploded left front perspective view showing the top and left exterior sides and the right and bottom interior sides of the rear portion thereof.

FIG. 4 is a left front perspective view of the rear portion showing the top and left exterior sides and the right and bottom interior sides of the rear portion thereof.

FIG. 5 is a left front perspective view a portion of the interior assembly showing a left side portion thereof.

FIG. 6 is a side perspective view of an interior plate thereof; and,

FIG. 7 is a side perspective view of the cover plate thereof.

The broken-line disclosure in the views is understood to represent a fragmentary wall surface which is for illustrative purposes only and forms no part of the claimed design.
